UNITED STATES PATENT OFFICE.

EMIL GEMEINDER, OF PHILADELPHIA, PENNSYLVANIA.

LOCK-UP COVER FOR RECEPTACLES.

Application filed November 7, 1925. Serial No. 67,487.

My invention relates to new and useful improvements in a lock-up cover for receptacles, and has for its primary object to provide an exceedingly simple and effective device of this character which will securely hold a cover upon a receptacle so as to prevent accidental displacements thereof or its removal by dogs, cats and the like when such receptacle is used as a garbage can.

Another object of the invention is to improve the construction of the receptacle covered by my Patent Number 1,220,975, bearing date of March 27, 1917.

A further object of the invention is to provide a structure wherein the cover may be removed and the receptacle swung to a dumping position, and when returned to its normal upright position the cover will descend and seat itself.

A still further object of the invention is to provide a structure wherein the cover will be held against sideways movement relative to the receptacle until the bail has been moved to a certain position, and also wherein the cover will be held in certain open positions so that it will not contact with the ground or other surface upon which the receptacle is resting.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a side elevation of the receptacle embodying my invention showing the cover in a closed position, and illustrating by dotted lines a position that may be assumed when the cover is open.

Fig. 2, is a fragmentary sectional view of the receptacle in the region of one of the guide members or strips.

Fig. 3, is an enlarged perspective view of one of the guide members or strips.

In carrying out my invention as herein embodied, 5 represents a receptacle or container constructed from any suitable material and of any desirable shape or configuration, the upper open end of which is normally closed by a suitable cover 6, the lat-

ter having bearings 7 projecting from the outer edge or circumference thereof at diametrically opposite points, and said cover is further provided with a handle 8 on the top thereof in line with the bearings 7.

On the receptacle at diametrically opposite points are fastened the guide members or strips 9 so formed as to provide offset ends 10 so that when said members are secured to the receptacle by rivets 11, or their equivalent, passing thru holes 12 in the offset ends of the guide members, the central portions 13 of said guide members will be spaced from the outer surface of the receptacle as plainly shown in Fig. 2, and in these central or body portions 13 are formed longitudinal slots 14.

On each of the guide strips or members 9 is a keeper 15 which extends out from the outer face of the guide strip or member across the longitudinal slot therein to accommodate a limb of a bail 16, passing thru a bearing 7, the end of which is turned in so as to form a trunnion 17 projecting into and thru the slot 14 so as to be slideable in said slot. The keeper is fastened a short distance below the upper end of the slot 14 in order to leave a portion of the slot projecting above the keeper a distance equal to at least the diameter of the bail.

On each guide strip or member are also a pair of rests 18, one on each side of the keeper 15 and preferably so positioned that their upper surfaces or seats 19 are in the same plane as the upper edge of the keeper 15, and if found desirable these rests may be formed of the same strip of material from which the keeper is produced.

Secured to the receptacle adjacent the lower end or bottom thereof and disposed at a suitable point between the guide members 9 is a handle 20 which may be gripped for tilting the receptacle when moving it to a dumping position.

When the cover 6 of the receptacle is in a closed position, the inturned ends or trunnions 17 at the lower ends of the bail limbs lie in the lower ends of the slots 14 of the guide strips with intermediate portions of the bail limbs in the keepers 15, and the inter-connecting member of the bail overlying the cover and its handle 8 so that even tho the cover might be slightly raised it cannot be moved sidewise due to the engagement of the bail limbs with the keepers and

the trunnions with the guide members at points below the keepers as will be obvious. When it is desired to remove the cover, the handle 8 is grasped and pulled upward, and 5 the continued upward movement of said cover will lift the bail 16 by sliding its trunnions in the slots of the guide members until said trunnions reach the upper ends of the slots 14 above the upper edges of the keepers 10 15 at which time, due to the disengagement of the bail limbs from the keepers said bail may be swung outward with the cover into substantially the position shown by dotted lines in Fig. 1, where the limbs of the bail 15 will contact with one of the rests 19 on each guide member with the trunnion of the bail in contact with the edges of the guide members at the upper ends of the slots thereby holding the cover in an open position above 20 25 the supporting surface on which the receptacle is setting. If it is desired to tilt the receptacle to a dumping position, the handle 8 of the cover is retained in the hand of the user, and the receptacle lifted from its supporting surface at which time the handle 20 of the receptacle may be grasped and the receptacle swung about the trunnions. For transporting the receptacle from place to place the bail only is gripped and lifted 30 35 until the trunnions are at the upper ends of the slots in the guide members, at which time the receptacle may be bodily lifted and moved from place to place. When the handle 20 is released the receptacle will return to its normally upright position, and if the cover is off the receptacle it may then be released and bail and cover will drop downward causing the cover to automatically find its seat, as the bail will be held in an upright position and the bearings on the cover 40 will guide the latter to its proper place.

Of course I do not wish to be limited to the exact details of construction as herein shown as these may be varied within the

limits of the appended claims without de- 45 parting from the spirit of my invention.

Having thus fully described my invention, what I claim as new and useful is:

1. In a device of the character stated, a receptacle, vertically, longitudinally slotted 50 guide members on the outside of the receptacle at diametrically opposite points, keepers carried by the guide members and disposed across the slots below the upper ends of the latter, a bail having trunnions at the 55 lower ends of its limbs projecting into the slots of the guide members, the limbs of said bail coacting with the keepers when the bail trunnions are below the upper edges of the keepers to prevent swinging movement of 60 said bail, such swinging movement being permitted when the trunnions are above the upper edges of the keepers, and a cover slidably connected with the bail limbs.

2. The structure set forth in claim 1 65 wherein means are carried by the guide members to act as rests for the bail limbs when the bail is swung outward.

3. A receptacle, guide members fastened to the side wall of the said receptacle at diametrically opposite points and having the portions between the ends spaced from the receptacle wall and provided with vertical, longitudinal slots, a bail having inwardly 70 extending trunnions at the lower extremities of the limbs of said bail projecting into the slots of the guide members, keepers disposed across said slots adjacent the upper ends thereof, thru which the bail limbs pass, rests on both sides of the keepers to receive 75 80 the bail limbs when the trunnions are in the upper ends of the slots, a cover for the receptacle and bearings carried by the cover and coacting with the bail limbs for slidably connecting the cover to the bail.

In testimony whereof, I have hereunto affixed my signature.

EMIL GEMEINDER.
